UNITED STATES PATENT OFFICE

DEWEY M. PEEBLES, OF PITTSBURG, ILLINOIS

CAR COUPLING

Application filed February 27, 1926. Serial No. 91,261.

This invention relates to car couplings and more particularly to a coupling specially adapted for use in connection with cars used in mining coal and other materials.

5 One of the main objects of the invention is to provide a coupling of simple construction and operation which can be readily released without necessitating the operator entering between the cars. Another object 10 is to provide a coupling of the character stated which can be readily applied to mine cars of standard construction at comparative low cost. Further objects will appear from the detailed description.

15 In the drawings:—

Fig. 1 is a side view of a mine car of known type showing the coupling as applied,

Fig. 2 is a side view, partly in section and on an enlarged scale of the coupling as 20 applied,

Fig. 3 is an underneath view of a car showing the coupling link and associated parts as applied,

Fig. 4 is an end view of a car showing the 25 coupling member and associated parts as applied,

Fig. 5 is a side view of the coupling completed, partly in section, showing the position of the parts when the coupling is subjected to pull,

Fig. 6 is a section taken substantially on line 6—6 of Fig. 2.

This coupling is intended to be used in connection with mine cars C of known construction. Each car is provided with draw bars 1 and 2 fixedly secured thereto adjacent each end of the car. A block 3 is fixedly secured to the car structure adjacent the outer end of draw bar 1. This block has an opening 4 which accommodates a flexible member, such as a short length of chain 5 by means of which a coupling link 6 is connected to a guide block 7. The guide block is slidably mounted on a reduced portion 1^a of draw bar 1 by means of a cap plate 8 which fits over and about the reduced portion of the draw bar and is secured to the guide block by bolts 9 and nuts 10, or in any other suitable manner. The draw bar 1 is provided at its outer end with a head 11 having

shoulders 12 with which the guide block and cap plate contact when the block is moved into its outermost position. This provides means whereby pull to which the block 7 is subjected during travel of the cars is transmitted to the draw bar 1.

A shaft 13 is rotatably mounted transversely of the car and a chain 14 is secured at one end to this shaft and is wound thereon. Hand wheels 15 are secured on the shaft at each end thereof and the shaft is normally held against rotation in chain unwinding direction by gravity pawls 16 which are mounted on the sides of the car and engage with ratchet wheels 17 secured on the shaft adjacent the hand wheels. A tension spring 18 has its inner end secured to the other end of chain 14 and its outer end secured to a short length of chain 19 which is secured at its outer end to block 7. Normally, chain 14 is wound onto shaft 13 to a sufficient extent to place spring 18 under tension, the spring acting to hold link 6 against the outer face of the fixed block 3. This block is provided, in its outer face, with vertical and horizontal grooves 20 and 21, respectively, extending from opening 4. The grooves 20 receive the terminal portions of pins 22 carried by the base portion of link 6 and disposed at right angles thereto, and the grooves 21 receive the lateral portions of the base of the link. The grooves thus cooperate with the pins and the base portion of the link to normally hold the link in operative relation to block 3, the link being disposed in a horizontal position and extending forwardly from the block.

Draw bar 2 is provided at its outer end with an L-shaped element 23 having at its lower end a horizontally disposed arm 24 arranged in spaced parallel relation to the outer end portion 2^a of the draw bar. A plunger 25 is slidably mounted in grooves 26 and 27 formed in the opposed faces of arms 24 and portion 2^a of the draw bar 2, respectively. This plunger is urged outwardly in the coupling member formed by arm 24 and associated parts, by an expansion spring 28 confined between the plunger and arm 23^a of member 23, and its outward movement is limited by inwardly projecting flanges 29.

and 30 at the outer ends of arm 24 and portion 2^a of the draw bar. When the plunger 25 is in its operative position it is disposed beneath the lower end of a coupling pin 31, slideable through portion 2^a of draw bar 2 and through a bracket 32 extending upwardly from portion 2^a of the draw bar. Arm 24 is provided with an opening 33 disposed in alignment with the pin 31 so that the pin can drop by gravity through link 6 and opening 33 when the plunger 27 is displaced inwardly of the coupling member of draw bar 2, by entry of link 6 into this member during the coupling operation. As soon as the plunger 15 is forced inwardly from beneath the pin, the pin drops through the link and arm 24 completing the coupling operation, as in Fig. 5. This provides simple and efficient means whereby the cars can be automatically 20 coupled together without any necessity of the operator entering between the cars, thus eliminating the greatest source of injury to miners under the present practice of coupling the cars by hand.

25 A crank shaft 34 is rockably mounted in bearing members 35 transversely of the end of the car at which the coupling member or draw head of draw bar 2 is located. The shaft includes terminal crank arms by means 30 of which the shaft can be readily rocked normally from either side of the car, and a control crank member 36 connected by a chain 37 to the upper end of pin 31. When it is desired to uncouple the cars, shaft 13 is released and is turned in a direction to unwind chain 14 sufficiently to release spring 18 of all tension. This releases the pull on coupling link 6, after which pin 31 is raised into inoperative position by shaft 34 in which position it is held by plunger in the manner previously described. In practice but one pawl 16 and ratchet wheel 17 are used at a time, the pawl and ratchet wheel 17 used being those on that side of the car on which the operator is positioned; the pawl at the other side of the car being turned into inoperative position. After the cars have been uncoupled shaft 13 is rotated to wind the chain 14 thereon pulling link 6 toward block 3 and in operative relation thereto. The outer face 25^a of plunger 25 is of flattened V-shape so that the link will be guided to the central portions of the plunger when the coupling operation is initiated. This insures that the thrust will be transmitted centrally of the plunger and eliminates all possibility of binding such as might occur if the thrust were above or below the center of the plunger. The coupling means constructed in the manner illustrated and described is automatic during the coupling operation and can be readily operated from either side of the car during the uncoupling operation without the necessity of the operator entering between the cars at any

time, an important consideration in the coupling and uncoupling of cars.

What I claim is:

1. In a coupling means, a draw bar, a fixed block mounted forwardly of the draw bar, 70 a guide block slidably mounted on the draw bar, a coupling link, a flexible member for interconnecting said coupling link and said guide block, said fixed block having an opening therein through which said flexible member may be extended, rotatable means having a flexible member wound thereon, means for holding said rotatable means against rotation in one direction, and tensioning means arranged in said flexible means intermediate 75 said rotatable means and said guide block whereby said tensioning means may act on said guide block to urge said guide block in a direction away from said fixed block, the urging action imparted to said guide block 80 being transmitted through said first named flexible member to said coupling link to hold said coupling link against said fixed block.

2. In a coupling means, a draw bar having a slot formed therein, a fixed block having an 85 opening therein mounted forwardly of said draw bar, a guide block, means mounted in the slot in said draw bar for supporting said guide block, said fixed block having recesses formed in the forward face thereof, a coupling link having outwardly projecting pins 90 thereon, a flexible member extended through the opening in said fixed block between said coupling link and said guide block, a rotatable shaft, a flexible member connected to said guide block and disposed for winding on said rotatable shaft, ratchet and pawl means for holding said shaft against movement to prevent unwinding of said flexible means, a tensioning member in said last named flexible 95 means, said tensioning member being placed under tension when said flexible member is wound on said shaft to urge said guide block rearwardly whereby said flexible member extended between said guide block and said coupling link will urge said coupling link toward said fixed block to dispose said pins 100 on said coupling link in the recesses in said fixed block to hold said coupling link in a predetermined position.

In testimony whereof I affix my signature.

DEWEY M. PEEBLES.
